[57] **CLAIM**

The ornamental design for a motor housing cover for a ceiling fan, as shown and described.

DESCRIPTION

FIG. 1 is a front elevational view of a motor housing cover for a ceiling fan showing my new design;

FIG. 2 is a rear elevational view thereof;

FIG. 3 is a left side elevational view thereof (a right elevational view thereof is the same as the left elevational view of FIG. 3);

FIG. 4 is a top plan view thereof;

FIG. 5 is a bottom plan view thereof; and,

FIG. 6 is a perspective view thereof.
